UNITED STATES PATENT OFFICE

EDWARD NAGLE, OF NEW PHILADELPHIA, OHIO, ASSIGNOR OF ONE-HALF
TO CHARLES C. DAVIS, OF UHRICHSVILLE, OHIO

LOCOMOTIVE BRAKE SHOE

Application filed June 14, 1928. Serial No. 285,416.

The present invention is directed to improvements in locomotive brake shoes.

The primary object of the invention is to provide a device of this character so constructed that the brake shoes will be maintained in engagement with the heads without the use of bolts.

Another object of the invention is to provide a device of this character constructed in such manner that the shoe can be easily and quickly attached to or removed from the head.

With these and other objects in view, this invention resides in the novel features of construction, formation, combination and arrangement of parts to be hereinafter more fully described, claimed and illustrated in the accompanying drawing, in which,—

Figure 1 is a side elevation of the device.

Figure 2 is a rear view of one of the shoes.

Figure 3 is a sectional view on line 3—3 of Figure 2.

Figure 4 is a sectional view on line 4—4 of Figure 2.

Referring to the drawing, 1 designates the body of the brake shoe which is longitudinally curved, as usual to conform to the curvature of the wheel, said body having a groove 2 formed in its front face for receiving the flange 2' of the locomotive wheel.

The body 1 has a recess 3 formed in its rear face, the end walls 4 thereof being beveled, as at 5. It will be observed upon reference to Figure 4 that the outer wall 6 of the recess is of less height than the inner wall 7 thereof.

The wall 6 gradually increases in height between its ends in order that a stop 8 will be provided, the purpose of which will be later explained.

The head 9 is provided with spaced flanges 10—10 provided with openings 11 for the passage of a bolt 12 adapted to engage in the hanger 13 when said hanger is engaged between the flanges. The hanger, as usual, is pivoted at its upper end to the side frame 14 of the locomotive. The ends of the head are beveled, as at 5, to correspond to the beveled end walls of the recess 3.

In order to connect the head 9 to the shoe 50 it is necessary that the same be tilted slight-

ly, as indicated in dotted lines in Figure 4, thus permitting the same to slide over the stop 8 until fully within the recess 3, whereupon it can be readily straightened.

To connect the body and head to the hanger the body is placed upon the tread of the wheel, as shown in dotted lines in Figure 1, after which they are moved downwardly upon the tread until the hanger 13 is engaged between the flanges 10, whereupon the bolts 12 can be conveniently applied to secure the head, and thus the shoe in its operative position.

The inner side face of the body will slide upon the side frame 14, thus maintaining the body in proper position with respect to the head 9.

When it is desired to replace a broken or worn shoe it is only necessary to remove the bolts 12 whereupon the shoe can be moved upwardly along the wheel 10 until it occupies a position, as shown in dotted lines in Figure 1, whereupon the shoe and head can be conveniently disconnected.

From the foregoing description, it will be seen that a brake shoe has been provided which can be easily and quickly attached to the head without aid of bolts or the like.

Having thus described the invention, I claim:

A brake shoe comprising a body having a recess in its rear face, said recess having beveled end walls, the outer side wall of the recess being of less height than the inner side wall thereof and being curved to provide a stop, a head having beveled ends, said head being capable of being moved laterally over the outer side wall and stop for engagement in the recess, said end wall overhanging the ends of the head.

In testimony whereof I affix my signature.
EDWARD NAGLE. [L. S.]
